No. 11,888

July 27, 1880

UNITED STATES PATENT OFFICE.

CYRUS A. HODGES, OF TROY, AND TOBIAS S. HEISTER, OF LANSINGBURG, NEW YORK, ASSIGNEES TO OTIS G. CLARK AND DANIEL D. BUCKLIN, EXECUTORS OF THE LAST WILL OF N. S. VEDDER, DECEASED.

DESIGN FOR ELEVATED-OVEN COOKING-STOVE.

SPECIFICATION forming part of Design No. 11,888, dated July 27, 1880.

Application filed June 14, 1880. Term of patent 3½ years.

To all whom it may concern:

Be it known that we, CYRUS A. HODGES, of the city of Troy, in the county of Rensselaer and State of New York, and TOBIAS S. HEISTER, of the village of Lansingburg, in said county and State, have jointly invented and produced a new and original Design for Elevated-Oven Cooking-Stoves, of which the following is a specification, reference being had to the accompanying cut, print, or engraving of a stove having our said new design.

One feature of our invention is the design for the front of the elevated oven, the same consisting of the central compound ornament, A, composed of the inner flower-stem, b, on the background c, surrounded by the oval frame d, having projections e f, the quadrilateral surface g around said oval frame, and the ornamental border h, all shaped and arranged together substantially as represented in the aforesaid cut, and with or without the corner and top and bottom ornaments, i j, or either of them.

Another feature is the design for the panels of the end doors of the elevated oven, the same consisting of the compound central ornament, K, composed of the inner flower-stem, l, on the background m, surrounded by the oval frame n, having projections n' n², and the angular corner ornaments, o, on the raised quadrilateral surface p, all shaped and arranged as shown in the aforesaid engraving.

Another feature is the design for the panels at the ends of the fire-chamber, the same con-

sisting of the central floral ornament, q, on the 35 ornamental background r, bordered by the angular corner ornaments, s, surrounded by the smooth surface t and ornamental edging u, all shaped and arranged together as shown in the aforesaid print.

The design for the lower front panels, W, is composed of the outer molding, v, the central ornament, x, quadrilateral ground y, surrounded by the bead y', and the ornamented surface z, all shaped and combined as represented in the 45 aforesaid cut.

We do not herein claim the design for the skeleton shelf or rack V.

What we claim as our joint invention is—

1. The design for the front of the elevated 50 oven, composed of the parts A, b, c, d, e, f, g, and h, all shaped and arranged as specified and shown.

2. The design for the panels of the oven-doors, composed of the parts K, l, m, n, n', n², o, 55 and p, all shaped and arranged as shown and described.

3. The design for the lower end panels, consisting of the parts q, r, s, t, and u, all shaped and arranged as set forth.

In testimony whereof we hereunto set our hands, in the presence of two subscribing witnesses, this 9th day of June, 1880.

CYRUS A. HODGES.
TOBIAS S. HEISTER.

Witnesses:

JAMES A. GILMAN,
CHESTER BASCOM.
